UNITED STATES PATENT OFFICE.

GEORGE E. COX, OF NIAGARA FALLS, NEW YORK, ASSIGNOR TO AMERICAN CYANAMID COMPANY, OF NEW YORK, N. Y., A CORPORATION OF MAINE.

CYANAMID-OVEN.

1,326,442.

Specification of Letters Patent. Patented Dec. 30, 1919.

Application filed July 21, 1919. Serial No. 312,183.

To all whom it may concern:

Be it known that I, GEORGE E. Cox, a citizen of the United States, residing at Niagara Falls, in the county of Niagara and State of New York, have invented certain new and useful Improvements in Cyanamid-Ovens; and I do hereby declare the following to be a full, clear, and exact description of the invention, such as will enable others skilled in the art to which it appertains to make and use the same.

This invention relates to cyanamid ovens and has for its object to improve the linings of the same in a manner less costly than has been heretofore proposed.

With this object in view the invention consists in the novel parts and combinations of parts all as will be more fully hereinafter described and particularly pointed out in the claims.

Referring to the accompanying drawings forming a part of this specification in which like numerals designate like parts in all the views:

25. Figure 1 is a sectional view of a cyanamid oven lined according to this invention;

Fig. 2 is a detail view taken on the line 2—2 of Fig. 1;

Fig. 3 is a view similar to Fig. 1, showing 30 a somewhat modified form of the invention; and

Fig. 4 is a detail view taken on the line 4—4 of Fig. 3.

In order that the precise invention may be 35 the more clearly understood, it is said:

In the manufacture of cyanamid it has been heretofore the practice to take a finely ground carbid and insert the same into a container. This container filled with its 40 charge of carbid is placed in an oven lined with suitable refractory and insulated material. A suitable electric resistor is inserted axially through the container in a space provided therefor.

45. The lid is placed on the oven, nitrogen admitted and the current turned on to the resistor. At a temperature upward of 800°-1000° C. the hot carbid adjacent to the resistor takes up nitrogen and is converted into cyanamid. This reaction progresses outwardly throughout the mass until the whole is more or less completely converted to cyanamid, when the said mass is left to cool. The container with its content 55 of cyanamid is then removed and the oven

made ready for a new charge. The great wear and tear on the metal container when subjected to the high temperature incident to the reaction, is a source of serious trouble and expense, and it becomes dented and battered through handling which makes it difficult to distribute its content of solid cyanamid.

In order to obviate this difficulty and especially because of the excessive cost of 65 metal containers, a substitute for the same was found, consisting in a paper sleeve which was inserted into the oven and then filled with carbid, after which nitrification was started in the usual manner. 70 This paper sleeve must be manufactured from stout paper and of definite dimensions and even with the greatest care it would frequently tear or split from the pressure of the contained powdered carbid. An annular space had to be left between the paper container and the oven for inserting the proper equipment for placing the paper and holding it in place during the filling with carbid as well as to assist in the distribution 75 of the nitrogen. This annular space reduced the capacity of a given sized oven by the amount of this dead space, and thus increased the cost of the equipment and 80 housing.

85. It was later found possible to do away with the metal container or the paper container entirely. In place of using these said containers it was found that the ordinary cyanamid oven, cylindrical in form and provided with the usual refractory lining, could be lined with a single sheet of paper or preferably corrugated strawboard; the usual paper cylinder for forming a space for the resistor could be inserted, and then the 90 whole oven could be filled with carbid, all as will be clear from the prior U. S. Patent #1315678, dated Sept. 9, 1919, to W. H. Middleton, assigned to the American Cyanamid Company, and entitled Process of manufacturing cyanamid. In this manner the strawboard or paper could be merely laid around the inside wall of the oven with a suitable lap without special forming. Operating according to this latter procedure a given oven 100 would hold say 35 per cent. more carbid than where the said prior paper sleeve was used and nearly 50 per cent. more than where the metal container was used, and this without any change whatever in the structure of the 105 oven.

oven itself. In such cases the nitrogen was led through a hole at the side and bottom of the oven which was covered with broken strips of corrugated strawboards extending to the center tube and also to the top of the corrugated lining and in this way nitrogen was distributed through the broken up strawboard both to the center and to the top of the oven.

This latter method gave very excellent results, because it produced a high fixation and a large capacity per oven, but it is necessary that a heavy corrugated strawboard be used, for in case of using a light plain paper where the oven walls are smooth it will not allow for a free passage of nitrogen around the carbid, and in the case of an uneven projection from the oven walls, with this lighter paper there is experienced a considerable loss in the tearing of the paper. Also, one cannot rely on an absolutely even distribution of nitrogen in and around the mass in this said procedure, for while the fixation is high it is not as uniform as might be desired in all cases.

In this invention, on the other hand, I have found it desirable to line the inside wall of the oven with a piece of wire screening, or netting, and place the plain paper against this said wire screening, or netting. I also insert the usual paper cylinder in the center for forming a space for the resistor and I fill up the whole oven with carbid. In place of using a wire screen, the bricks of the oven lining itself may be molded or cut with projections, the span from tip to tip of which are not so great as to allow the paper lining to tear. Plain paper is then placed inside of the oven against the brick work with a suitable lap, and the operations carried on as described above.

In this manner I am able to secure a very uniform flow of nitrogen gas around and about the carbid which gives in practice an exceedingly uniform fixation of the carbid for the formation of cyanamid. It also gives as high a fixation as is obtained by the previous methods. This method also has the advantage of allowing me to use a cheaper form of lining than is possible by the previous process and with less trouble and difficulty in handling the same. I prefer to have the oven slightly tapered as shown, it being somewhat larger in diameter at the top than at the bottom, because when the carbid fixes the nitrogen with the formation of cyanamid, the latter shrinks away from the oven lining somewhat, and by the use of a tapered oven the charge may be more easily withdrawn.

Referring to the accompanying drawings, 1 indicates any suitable outer shell, 2 any suitable refractory lining, preferably tapered as shown, 3 a cover having a refractory lining 4, and the depending rim 5, dip-

ping into a sand seal 6, held by the annular member 7 as shown.

On the inside surface of the refractory lining 2, I preferably lay wire cloth, or a wire netting 8, and inside the netting 8 I lay preferably smooth paper sheets 9. At the center of the oven I place the paper or other combustible tube 10 for the accommodation of the resistor 11, and at the side near the bottom I provide the nitrogen inlet 12. Between the inlet 12 and the tube 11 I may place a tube of crumpled up, or corrugated paper 13 as shown, in order to lead nitrogen to the resistor, and above this tube 13, I may lay wire cloth 14 as shown in Fig. 80 1, or it may be omitted as shown in Fig. 3, if the tube 13 is made sufficiently strong to keep open a passage for the nitrogen. A portion 15 of the paper 9 may also extend above the wire cloth 14 as shown in Fig. 1. 85

The modified construction illustrated in Figs. 3 and 4 is substantially the same as that disclosed in Figs. 1 and 2, except the inside surface of the refractory lining 2 is roughened as indicated at 18. The projections 19 are suitably molded in the bricks, but may be otherwise produced, and they are spaced sufficiently close to each other to prevent the tearing of the paper lining 20. 90 21 represents hooks that are placed in the carbid charge 22 to facilitate the withdrawal of the formed cyanamid from the oven.

It will thus be seen that I have discovered that the space left by the meshes of wire cloth, or a wire screen, will not be filled up after the combustible paper lining 9 is destroyed, and that it will be sufficient to furnish a passage for the feeding of the nitrogen in the process. In other words, it will 105 now be clear that I have discovered, it is not necessary to even go to the expense and trouble that are incident to the highly efficient process disclosed in the said Middleton application above mentioned; for I may even 110 avoid a corrugated lining for the oven, and employ plain paper, provided there are present supporting projections for said paper spaced so close that it will not tear.

Of course, upon nitrification the paper 115 around the inside of the oven chars and the ingot of cyanamid shrinks away from the walls and screening sufficiently, so that if a proper taper is given to the oven lining 2 it is a simple matter to withdraw the ingot. A 120 crane picks up the ingot of cyanamid as by attaching hooks to the rings on the ends of the iron rods 21, and carries it out of the oven.

A great advantage in this improved process lies in the fact that a very cheap grade of plain paper 9 can be used. The wire screening 8 may be used over and over again and when the brick in the walls of the oven lining are molded or cut in grooves 18-125 130

no appreciable replacements are necessary. Also, a perfectly uniform passage of nitrogen is thus provided in and around the mass 22, and there is combined with the previous 5 advantages claimed for the full oven, a better reflection of heat to the mass from the lining 2, resulting in more perfect fixation at the outside of the ingot 22. As a result of these improvements with identically the 10 same carbid, I obtained in actual practice, a more uniform absorption of nitrogen and consequently a more uniform product with as good a carbid efficiency as is obtained in the last mentioned previous process. It is 15 evident that those skilled in the art can vary this procedure without essentially changing its principle and I, therefore, do not wish to be restricted to the above disclosure, except as may be required by the 20 claims.

What I claim is:—

1. In a cyanamid oven provided with a refractory lining, the combination of a combustible, substantially smooth, paper lining 25 and a plurality of supporting means separated by interstices, located between said refractory lining and said paper lining, substantially as described.
2. In a cyanamid oven provided with a refractory lining and a resistor the combination of a combustible tube surrounding said resistor; a plurality of supporting non-combustible surfaces separated by interstices and in close proximity to said refractory lining; 30 a substantially smooth combustible sheet ma- 35

terial resting against said supporting surfaces; means to introduce nitrogen into said oven; and means to convey the introduced nitrogen to said tube, substantially as described.

3. In a cyanamid oven, having a tapered inside refractory lining; non-combustible supporting surfaces separated by interstices associated with said lining; and a paper lining resting on said surfaces, substantially as described. 40 45

4. The process of producing commercial cyanamid, which consists in providing a cyanamid oven with an upwardly flaring refractory lining; associating with said lining 50 non-combustible supporting surfaces separated by nitrogen conveying spaces; resting on said surfaces a combustible lining; providing spaces for an igniting resistor and for the admission of nitrogen to said resistor; substantially filling the interior of said last named lining with calcium carbid except for said last named spaces; implanting a lifting means in the carbid charge to facilitate the removal of the ingot from the 55 tapering oven; admitting nitrogen to said carbid; and igniting the charge, substantially as described.

In testimony whereof I affix my signature, in presence of two witnesses.

GEORGE E. COX.
